UNITED STATES PATENT OFFICE

159,467

SIFTER

Lucille M. Barbery, Minneapolis, Minn., assignor
to Foley Manufacturing Company, Minneapolis,
Minn., a corporation of Minnesota

Application June 24, 1949, Serial No. 3,516

Term of patent 14 years

(Cl. D44—29)

To all whom it may concern:

Be it known that I, Lucille M. Barbery, a citizen of the United States, residing at Minneapolis, county of Hennepin, State of Minnesota, have invented a new, original, and ornamental Design for a Sifter, of which the following is a specification, reference being had to the accompanying drawing, forming part thereof.

Figure 1 is a top plan view of a sifter, showing my new design;

Figure 2 is a side elevational view from the left side; and

Figure 3 is a side elevational view from the handle side.

I claim:

The ornamental design for a sifter, as shown.
LUCILLE M. BARBERY.
